UNITED STATES PATENT OFFICE.

ELIAS J. EMERY, OF PORTSMOUTH, NEW HAMPSHIRE.

ARCH-SUPPORT.

1,125,989.

Specification of Letters Patent.

Patented Jan. 26, 1915.

Application filed January 8, 1914. Serial No. 810,897.

To all whom it may concern:

Be it known that I, ELIAS J. EMERY, a citizen of the United States, residing at Portsmouth, in the county of Rockingham and State of New Hampshire, have invented certain new and useful Improvements in Arch-Supports, of which the following is a specification, reference being had therein to the accompanying drawing.

10 This invention relates to means for securing an arch-support outside of a shoe or other article of footwear and under the instep portion thereof, and it provides simple and effective means of this kind that 15 will be covered by the support or pad or other parts, whereby there are no projections that will be liable to trip the wearer.

When read in connection with the description herein, the details of construction and 20 arrangement of parts contemplated by the invention will be apparent from the accompanying drawing, forming part hereof, wherein embodiments of the invention, as applied to a shoe, are disclosed, for purposes of illustration.

While the disclosures herein now are considered to represent preferable embodiments of the invention, it is to be understood that it is not the intention to be limited necessarily thereto in interpretation of claims 30 hereinafter, as it is obvious that changes within the scope of the claims can be made without departing from the nature and spirit of the invention.

35 Like reference-characters refer to corresponding parts in the views of the drawing, of which—

Figure 1 is a bottom view of a shoe with a pad thereon; Fig. 2 is a top view of a 40 pad with attaching means thereon; Fig. 3 is a view of a portion of a sole with attaching means thereon; Fig. 4 is a view of one of the attaching members on the pad; Fig. 5 is a view of another attaching member on the pad; Fig. 6 is a view, partly in longitudinal section, illustrative of other means for securing the pad; Fig. 7 is a view of a portion of a shoe having in its heel a socket member that is one of the securing means shown by Fig. 6; Fig. 8 is a view of a pad and securing members used in the form shown by Fig. 6; Fig. 9 is a view of the socket member used in the form shown by Fig. 6; Fig. 10 is a view of a 50 pad having another arrangement of securing members similar to those used in the

form shown by Figs. 2, 4, 5, and 11; and Fig. 11 is a longitudinal sectional view of a pad.

Having more particular reference to the drawing, 12 designates a shoe or other article of footwear, 13 the heel, 14 the instep portion of the sole, and 15 the tread portion of the sole.

The support includes a pad 16, preferably of rubber or other similar resilient, pliable, and elastic material, shaped to fit the contour of the sole at the instep and to afford a bearing-surface under the instep, and arranged to have its rear end abut, or nearly abut, the front face of the heel and its front end extend to, or nearly to, the rear end portion of the sole, whereby a support is afforded between the heel and the ball of the foot of the wearer. As shoe-carried members of the means for holding the pad in place, there are secured to the under surface of the sole two sheet-metal members or straps 17, one near the heel and the other farther in advance of the heel. These members are held on the shoe by screws or other suitable fastenings 17^a near their ends, and between its ends each member is formed with a downwardly-deflected portion or web 17^b, whereby a space or passageway is afforded between it and the surface of the sole.

As one of the members on the pad to co-operate with a member 17 on the shoe, there is provided a member 18, which comprises a flat web portion 18^a, having at one end an upturned flange 18^b, from the upper portion of which extends a lug or flange 18^c, which is disposed over, and in substantially parallel relation to, the web 18^a. In order to increase the holding power of the material of the pad to the member 18, the web is formed with an opening 18^d. As the other member on the pad to co-operate with another member 17 on the shoe, there is provided a member 19, which comprises a substantially U-shaped web portion 19^a, having upwardly extending from between its limbs a flange 19^b, from the upper portion of which extends a lug or flange 19^c, which is disposed over, and in substantially parallel relation to, the web 19^a.

Both of members 18 and 19 have their web portions embedded in the material of the pad, this association being effected preferably when the pad is molded, in disposition substantially parallel to the upper face

of the pad, and with their lugs 18^c and 19^c disposed slightly above that face, and extending, respectively, toward the ends of the pad, and the members are held in the pad by vulcanization or otherwise. The members are placed in the pad in such distance apart that, when their lugs are brought into engagement with the members 17 on the shoe, they will have disposition between the sole and the web portions 17^b. Preferably, 10 the member 18 is placed near the rear end of the pad, and the member 19 near the front end.

To place the pad on a shoe, the rear lug 18^c is inserted between the rear web 17^b and the sole, and then the pad is bent and the front lug 19^c is forced between the front web 17^b and the sole, when the pad returns to its normal unbent condition. The pad 20 may be removed by a reversal of this operation.

If desired, two members 18 may be placed in the pad as shown by Fig. 10, or two members 19 may be so placed, or a member 18 and a member 19 may be so placed; that is, with their lugs extending toward each other, instead of toward the ends of the pad as shown by Fig. 2. In that case, when the pad is to be placed on a shoe, the pad is stretched sufficiently to bring the lugs over the webs of the members 17, and then the lugs are drawn by contraction of the pad into position between the webs and the sole, whereby the pad is held in place; or 30 one of the lugs may be placed over one of the webs, and the other lug then sprung over the other web. The pad may be removed by stretching it sufficiently to afford disengagement of the lugs from the webs. There also may be used on the pad, 40 in place of members 18 and 19, a member 20, having a web 20^a, embedded in the pad, and a flange 20^b extending rearwardly therefrom and from the rear end of the pad in a plane slightly above the upper surface of the pad; and, at the front end portion, the pad may have embedded therein near its upper surface a plate 21, having a hole 21^a, and in this case the pad below the plate is formed with an opening or socket 21^b to 50 permit a brad 22 or the like to be passed therewith and to be driven through the hole 21^a into the shoe, whereby the front end of the pad is held in place. This arrangement 55 is shown clearly by Fig. 8.

When member 20 is used, there is provided a member 23 to coöperate therewith to maintain the rear end of the pad in position. Member 23 comprises a flat web portion 23^a, along the side edges of which are upturned flanges 23^b, increasing in height from rear to front, whereby a wedge-like member is formed. This member is driven in between the heel and sole of the shoe, the 65 edges of the flanges contacting with the sole

and the web with the heel material, and there is provided thereby a socket open at the front end that is adapted to receive the flange or lug 20^b. To place the pad on the shoe, the flange 20^b is inserted in the socket and then the brad is driven through the plate 21 into the sole. 70

The upper face of the pad is slightly rounded or dished, and around the edges there is a ridge 16^a, so that, when the pad 75 gives under weight imposed on it, the edges remain in contact with the sole. Thus there is avoided the tendency that would be had by the edges of a flat-top pad to separate from the sole and to afford a space for collection of dust, mud, and the like and thereby to injure the neat appearance of the article on a shoe and to some extent interfere with its function. Further, the dished and rigid formation of the upper face of 80 the pad affords a space for accommodation of the straps on the shoe and the lugs that engage with them and prevents the access of fouling matter thereto. 85

In order to increase the resiliency of the 90 pad, it may have opening into its upper face one or more recesses or cavities, of which one is shown and designated by 16^b centrally located between the two retaining members. As shown, the recess is rectangular in shape and extends from one holding member to the other. 95

If desired, a wear-plate 24 may be disposed on the lower surface of the pad to protect the latter from undue wear, and preferably 100 the plate is roughened to prevent slipping. The wear-plate is held in place by a shank 24^a extending upwardly therefrom through the material of the pad and through a plate or washer 24^b in the recess 16^b, the upper 105 end of the shank being screw threaded and having thereon a nut 24^c adapted to be turned against the washer and to draw the wear-plate against and to hold it on the lower surface of the pad. 110

Having thus described my invention, what I claim as new, and desire to secure by Letters Patent, is—

1. An arch-support pad arranged to be placed on the sole of an article of footwear 115 and having on its upper face retaining members arranged to coöperate with holding members on the sole and having a recess opening into the upper face, and on the lower face of the pad a wear-plate having a 120 shank extending upwardly in the pad into said recess, and a retaining member on said shank within said recess.

2. In combination, a footwear sole and a 125 pad of resilient and elastic material arranged to be positioned under the instep portion thereof, strap members on the sole above the pad, and two members on the pad each comprising a web portion embedded in the pad and a flange above the upper face 130

of the pad in substantially parallel relation thereto and extending in a direction opposite to that of the flange of the other member, the arrangement being such that on temporary distortion of said pad said flanges may be brought into and out of engagement with said strap members.

3. An arch-support pad of resilient and elastic material having two retaining members each comprising a web portion embedded in the pad and a flange above the upper face of the pad in substantially parallel relation thereto and extending in a direction

opposite to that of the flange of the other member, the arrangement being such that on temporary distortion of said pad said flanges may be brought into and out of engagement with holding members on a foot-wear-sole.

In testimony whereof I affix my signature in presence of two witnesses.

ELIAS J. EMERY.
